(57) **CLAIM**

The ornamental design for a camera as shown and described.

DESCRIPTION

FIG. 1 is a top, front and right perspective view of a camera showing our new design.

FIG. 2 is a front elevation view of the camera shown in FIG. 1.

FIG. 3 is a rear elevation view of the camera shown in FIG. 1.

FIG. 4 is a left elevation view of the camera shown in FIG. 1.

FIG. 5 is a right elevation view of the camera shown in FIG. 1.

FIG. 6 is a top plan view of the camera shown in FIG. 1; and, FIG. 7 is a bottom plan view of the camera shown in FIG. 1.

The broken lines in the drawings depict portions of the camera that form no part of the claimed design. The break lines depicted with broken lines in the drawings are included to show a symbolic break and the appearance of any portion of the article between the break lines forms no part of the claimed design.
